THREAD WINDING MECHANISM

Louis E. Lovett, Cleveland Heights, Ohio, assignor to Industrial Rayon Corporation, Cleveland, Ohio, a corporation of Delaware

Application October 26, 1936, Serial No. 107,512

4 Claims. (Cl. 242—18)

This invention relates to the winding of artificial silk thread or the like upon a bobbin, spool or other collecting device, and, more particularly, to improvements in traverse mechanisms therefor.

Conventional forms of traverse mechanisms conduct the thread to the collecting device in such manner that an extremely dense package results. Difficulty is experienced in processing a dense package of this kind inasmuch as treating fluids do not readily penetrate it, in consequence of which fact a considerable length of time is required to complete the various processing operations. Among other things, the present invention provides means for forming a thread package lending itself, by virtue of its high degree of porosity, to ready penetration by processing fluids.

For illustrative purposes, the invention will be described in connection with the viscose process of manufacturing artificial silk thread, although it is to be understood that the invention may be applied to other processes such as the cuprammonium, cellulose acetate and cellulose nitrate processes. Its advantages are particularly important in the viscose process, in which viscose is extruded through a spinneret into an acid coagulating bath in which it coagulates as and from which it is withdrawn in the form of regenerated cellulose thread. After the collecting spool has been filled, it is removed to a wash trough wherein washing liquid is forced through it in order to remove the acid which is present in the thread. Whereas as much as five hours have been required heretofore to remove the acid, by the present invention this time may be reduced to less than two hours.

One form of apparatus resulting in the winding of the thread upon the collecting spool with the desired degree of porosity will be described in connection with the apparatus illustrated in the accompanying drawings. Figure 1 is a side elevation of one section of a spinning machine to which the invention is applied. Figure 2 is a corresponding plan. Figure 3 is a view from line 3—3 of Figure 1. Figure 4 is a section on the line 4—4 of Figure 1, parts being broken away. Figure 5 is a detail, partly in section, of a portion of the machine on an enlarged scale. Figure 6 is a plan of a portion of the machine showing the relation of parts at the completion of the thread-collecting operation. Figure 7 is a side elevation of a portion of Figure 6. Figure 8 is a section on the 8—8 of Figure 3. Figure 9 is a diagrammatic representation illustrating gen-

erally the arrangement of parts in the apparatus of the invention.

The spools 10, upon which are collected threads 11 from a corresponding number of spinnerets (not shown), are mounted upon opposite ends of transverse shafts 12. Each shaft 12 is mounted in a gear box 13 and is rotated by means of gears 14, 15, the latter of which is carried upon a line shaft 16 extending longitudinally of the machine. Shaft 16, supported upon frame bearings 17 at opposite ends of each section of the machine, is rotated by power from motor 18 transmitted through chain 19, a variable transmission which includes pulleys 20, 21, and chain 22. Pulley 20 is carried upon a shaft 23 rotatably mounted in bearings carried by the frame of the machine.

To carry the thread back and forth across the face of each of the collecting spools 10, it is passed through a thread guide eye 25 at the lower end of an arm 26 depending from rocker shaft 27. Rocker shaft 27, carried by bearings 24, is actuated by means of a cam contained within cam box 28 rotated through gears 29 and 30 by line shaft 16. Through the operation of the cam, a lug 31 upon the exterior of the cam box 28 is caused to reciprocate back and forth, as shown by full and dotted lines in Figure 2. Pivotedly connected to this lug 31 is a lever 32 fulcrumed at pin 33. At its outer end, lever 32 is pivoted by pin 35 on a cross bar 34 reciprocating through guide plate 40. Pin 33 and pin 35 engage within longitudinal slots of lever 32.

Centrally of the cross bar 34 is fastened a block 36 to which are pivotally connected links 37 the outer ends of which are forked. Within the forked end of link 37 is received arm 38 fastened to rocker shaft 27 by means of which rocker shaft 27 is actuated. Link 37 passes through a slot 39 of guide plate 40 to permit up and down movement of link 37 due to the oscillatory movement of arm 38. The arm 38 is of less thickness than the distance between the prongs of the forked end of lever 37 in order to permit a limited amount of transverse movement of the arm 38.

The fulcrum pin 33 for lever 32 is carried by a bracket 42 secured to an endwise movable bar 43. Bar 43 is squared and is carried within squared bearings 44 which permit the bar to have endwise but not rotary movement. At one end of bar 43 are formed screw threads 45 which are used in causing an axial movement of the bar 43 for the purpose of shifting the fulcrum pin 33 during the operation of the machine. Carried upon the screw threads 45 is a nut 46 hav-

- ing a sprocket 47 upon its exterior which nut is positioned between bracket arms 48 of the frame in such manner as to prevent its endwise movement, whereby upon rotation of the nut 46 the bar 43 is caused to move endwise. Adjustable stop 80 determines the initial position of bar 43.
- Nut 46 is rotated in timed relation to the spools through a driving connection receiving its power from the motor 18. This power takeoff includes a gear 50 upon shaft 23 which gear 50 drives a gear 51. Gear 51 is carried upon a shaft 52 which is journaled in cross pieces 53 of gear supports 54. A worm 55 secured to shaft 52 drives gear 57 upon shaft 56. To the latter shaft is fixed gear 58, which drives gear 59. To gear 59 is secured an eccentric pin 60 upon which is pivoted a link 61 pivoted at its upper end to a pawl arm 62. Oscillation of pawl arm 62 drives ratchet wheel 63, carried upon a shaft 64, in the direction of the arrow in Figure 3. Movement of shaft 64 in the opposite direction is prevented by detent means 65. Gear 66 secured to shaft 64 drives sprocket 67 through a gear train generally indicated by 68. Sprocket 67, through chain 69, drives the sprocket 47 upon nut 46.
- Through operation of the structural arrangement above described, a package of thread will be collected upon the spools and the ends of the packages will be conically shaped as shown in Figure 6. These conical ends are formed by progressive movement of fulcrum pin 33 under the influence of shaft 43. As the machine operates, and the fulcrum pin is urged away from driving lug 31, the lever arm determined by the distance between pins 33 and 35 is shortened with the result that cross bar 34, links 37, arm 38 and consequently thread guide eye 25 have a constantly decreasing extent of movement. Through the speed reducing action of pawl 62, ratchet wheel 63, and its associated driving connections, the extremities of travel of thread guide eye 25 are brought slightly closer together as each new layer of thread is deposited on the spool.
- It is also common practice to oscillate the traverse arm 26 in such timed relation to the rotation of spools 10 that successive turns of thread will tend to be superimposed. This is accomplished if the spool, for each complete oscillation of the traverse arm, rotates a whole number of turns and a fractional portion of a turn which fraction has an odd number as its denominator. For example, the spool may rotate $8\frac{1}{25}$ turns for each complete swing of the traverse arm, in which case, starting with the 203rd turn, the thread being laid down will be laid directly upon a thread earlier laid down, and open diamonds will be formed by the thread. However, with such conventional arrangements, each new turn of thread will not be exactly radially outwardly from an inner turn since the thread passing from the thread guide eye to the package will assume a different angular relation as the package increases in thickness. Since the point of contact of the thread with the package will tend to shift around the spool, the new layers of thread will lie over the openings within the diamonds earlier formed and thus obstruct the free passage of processing fluids.
- To overcome these disadvantages and form diamonds the openings of which are unobstructed throughout the thickness of the package, the invention provides means for causing a recessional movement of the thread guide eye as the package increases in thickness. To achieve best

results, it is desirable that the thread guide eye 25 be positioned initially directly below the outside of the collecting spool, so that the thread passes vertically to the spool as shown in Figure 1. The recessional movement of the thread guide eye carries the thread guide eye laterally away from the spool in a direction perpendicular to the length of thread between the thread guide eye and the spool. By moving the thread guide eye away from the spool at the rate at which the package increases in thickness, the thread will always pass in a vertical direction to the package and will contact with it in the same manner.

This recessional movement is effected by a screw shaft 70 in axial alignment with rocker shaft 27 connected to the latter by a coupling member 71 which permits their relative rotation. Screw shaft 70 is squared at 72 along a portion of its length and this portion passes through frame upright 73 which prevents turning movement of the screw shaft. Positioned upon the screw shaft between upright frame members 74 is a nut 75 having upon its exterior a sprocket 76. A chain 77 connects this sprocket 76 with a sprocket 78 upon shaft 64. In this manner nut 75 is rotated at the desired slow speed, utilizing pawl 62 and ratchet 63 for this purpose. A hand wheel 79 is keyed to sprocket 76 to make possible manual operation of the screw shaft.

In order to effect a corresponding recessional movement of a similar rocker shaft on the opposite side of the machine, chain 77 extends transversely of the machine to and around a second sprocket 76'.

During operation of the machine, as the package of thread increases in thickness, the rocker shaft will be caused to move axially as it is rotated. Such axial movement while the rocker shaft is being rotated is permitted by sliding movement of arm 38 along pin 41. As shown in Figure 6, at the completion of the winding operation, arm 38 is at the opposite end of pin 41 from its position in Figure 2. To restore the parts to their initial position, pawls 62 and 65 are lifted from ratchet wheel 63 and the hand wheel 79 rotated backward. Thereby bar 43, as well as rocker shaft 27, is returned in readiness for the next winding operation.

It is obvious that numerous changes may be made in the apparatus hereinabove described without in any way departing from the spirit of the invention; for example, a carrier bar of a different type may, if desired, be employed in lieu of the rocker shaft illustrated in the drawings. As already stated, although the apparatus hereinabove disclosed has been described as applied to the manufacture of viscose artificial silk thread, its usefulness is not limited thereto. It is intended that the patent shall cover, by suitable expression in the appended claims, whatever features of patentable novelty reside in the invention.

What is claimed is:

1. An oscillating thread guide mechanism comprising a rocker shaft; bearings for said rocker shaft permitting both rotational and axial movement of said shaft; an arm rigidly secured to said rocker shaft which arm is provided with a thread guide eye; means for actuating said rocker shaft to oscillate said arm; and means operated in timed relation to said first-mentioned means for moving said rocker shaft through said bearings in an axial direction.

2. Thread winding mechanism comprising a rotatable collecting spool; an arm provided with a thread guide eye; a carrier bar to which said arm is secured; supporting means for said carrier bar permitting it to have two independent motions; means actuating said carrier bar to cause it to move said thread guide eye back and forth across said collecting spool during one of its two independent motions; and means actuating said carrier bar to cause it to move said thread guide eye progressively away from said collecting spool during the other of its two independent motions, the thread guide eye being moved away from said collecting spool at the rate at which the thread package being formed on said collecting spool increases in thickness. 5
3. Thread winding mechanism comprising a rotatable collecting spool; a carrier bar extending transversely of the axis of said collecting spool; an arm rigidly secured to said carrier bar which arm is provided with a thread guide eye, said thread guide eye being so disposed that the length of thread between the thread guide eye and the collecting spool extends at right angles to said carrier bar; means for actuating said carrier bar to cause it to move said thread 20
4. Thread winding mechanism comprising a plurality of collecting spools the axes of which are parallel; a carrier bar extending transversely of the axes of said collecting spools; a plurality of thread guide eyes supported on said carrier bar, each thread guide eye being so disposed that the length of thread between the thread guide eye and the collecting spool with which it is associated extends at right angles to said carrier bar; means for actuating said carrier bar in such manner as to move said thread guide eyes simultaneously across said collecting spools; and means for progressively moving said carrier bar 10 longitudinally to withdraw said thread guide eyes from said collecting spools at the rate at which the thread package being formed on said collecting spools increases in thickness. 15 20
